(57) **CLAIM**

The ornamental design for a part of a document feeder with a marquee riser for an image processing machine, as shown and described.

DESCRIPTION

FIG. 1 is a perspective view of a part of a document feeder with a marquee riser for an image processing machine in accordance with the present invention;

FIG. 2 is a front view thereof;

FIG. 3 is a right side view thereof;

FIG. 4 is a rear view thereof;

FIG. 5 is a left side view thereof; and,

FIG. 6 is a top view thereof.

The broken line drawings of other parts of the document feeder and of an image processing office machine in FIGS. 1-6 are for illustrative purposes only and form no part of the claimed design.

1 Claim, 4 Drawing Sheets

FIG. 1

FIG. 2**FIG. 3**

FIG. 4**FIG. 5**

FIG. 6
